Filed Oct. 4, 1971, Ser. No. 186,600

Term of patent 14 years

Int. Cl. D12—08

U.S. Cl. D14—6 B

FIG. 1 is a front elevational view of a removable side guard for automobile showing my new design;

FIG. 2 is a top plan view thereof;

FIG. 3 is a rear elevational view thereof;

FIG. 4 is an end elevational view thereof, to a larger scale; and

FIG. 5 is a sectional view thereof taken along line 5—5 of FIG. 1, to a larger scale.

The end not shown is a mirror image of the end illustrated in FIG. 4. The break lines indicate indefinite length.

I claim:

The ornamental design for a removable side guard for automobile, as shown and described.
